UNITED STATES PATENT OFFICE.

OLEY JOSIAH LEAR, OF NEWPORT, NEW HAMPSHIRE, ASSIGNOR TO SAMUEL D. LEWIS,
TRUSTEE, OF NEWPORT, NEW HAMPSHIRE.

MACHINE FOR CEMENTING SHOE-LININGS.

No. 921,261.

Specification of Letters Patent.

Patented May 11, 1909.

Application filed December 19, 1907. Serial No. 407,137.

To all whom it may concern:

Be it known that I, OLEY J. LEAR, a citizen of the United States, residing at Newport, in the county of Sullivan and State of 5 New Hampshire, have invented a new and useful Improvement in Machines for Cementing Shoe-Linings, of which the following is a specification.

My invention relates to improvements in 10 cementing side linings in shoe uppers with hot cement, at present a pot heated by steam is used for heating cement and is applied by hand with paint brush. While a machine constructed as herein shown and described 15 would be a cement and labor saving device.

The invention consists in the novel features of construction, combination and arrangement of parts, hereinafter fully described and pointed out in the claims.

20 In the drawing forming a part of this specification:—Figure 1 is a plan view of the device. Fig. 2 is a side view, looking toward the end of a rotatable drum. Fig. 3 is a section on the line 3—3 of Fig. 2. Fig. 4 is a 25 section on the line 4—4 of Fig. 2. Fig. 5 is a sectional view taken at right angles to Fig. 3.

In constructing the machine I employ a 30 base socket 1, in which is adjustably mounted a supporting standard 2, upon which is a hollow metal base 3, on which is mounted a shallow tray 4, and a tank 5 which is provided with an opening 6 affording communication with the tray and closed by a vertically movable gate 7 provided with an up- 35 right 8 which is engaged and operated by a pivoted lever 9. Upon the base 3 and on opposite sides of the tank are placed suitable bearings 10 through which run a steam pipe 11, the ends of which open into the hollow 40 base 3 and on opposite sides of the same.

A hollow axle 12 is mounted on the steam 45 pipe 11 between the bearings 10 and on said axle is secured a steam-tight drum 13, the pipe and axle being perforated as shown at 14, so that steam is admitted within the drum. Outside of the drum a gear-wheel 15 is fixed on the axle 14 and is inclosed by a suitable casing 16 which also incloses an intermeshing gear 17 mounted upon a power- 50 shaft 18, upon which shaft is also mounted a

fixed pulley 19 and an idle pulley 20 driven by a belt 21. An adjustable slide 22 is mounted on the tray 4 immediately in advance of the drum and by moving the same toward or away from the drum the amount of 55 cement carried upwardly by the drum from the tray 4 can be regulated. The front of the tank 5 carries a scraper 23, which rests upon the upper portion of the drum and scrapes therefrom the unused cement returning the same to the tank 5.

The cement is kept in the tank 5 and admitted as required into the tray 4 by lifting the gate 7. Steam is admitted through a pipe 24 into the base 3 and heats the bottoms 60 of the tray and tank and also passes through the pipes 11 into the drum which is heated sufficiently to prevent the cement thickening upon the drum surface. Two operators can work on each machine sitting upon sides of 65 the same, a suitable table being provided to hold the work. The operator takes the work to be cemented between the thumb and fingers of both hands pressing the work against the drum and then places the work 70 or parts upon which cement has been applied against the part to be cemented to it, smoothing down with the hand. Cement not taken from the drum by this operation will be removed by the scraper and will be 75 fed back to the tank where it will become re-heated, and can be again admitted to the tray.

Having thus fully described my invention, what I claim as new and desire to secure by 80 Letters Patent is:—

1. A device of the kind described comprising a hollow base, a steam pipe discharging into said base, a tray mounted on the base, means for feeding heated cement to the tray, 85 a continuous steam pipe leading from the ends of the base and having a perforated portion above the tray, and a hollow drum mounted rotatably on said pipe and inclosing the perforated portion of the pipe. 90

2. A device of the kind described, a hollow base, a tray mounted upon said base, a tank mounted on the base and communicating with the tray, a gate regulating communication between the tank and tray, a rotatable 95 shaft 100

drum receiving cement from the tray, and means for admitting steam into the hollow base and from the base into the drum.

3. A device of the kind described comprising a steam-heated base, a steam-heated drum, a tank arranged in the rear of the drum, a tray arranged beneath the drum, means for regulating the flow of cement from

the tank to the tray, and an adjustable slide carried by the tray and movable and toward 10 and away from the drum.

OLEY JOSIAH LEAR.
